UNITED STATES PATENT OFFICE.

ALEXANDER W. NELSON, OF NEWARK, NEW JERSEY, ASSIGNOR TO NELSON TOOL & MACHINE COMPANY, INCORPORATED, A CORPORATION OF VIRGINIA.

ADJUSTABLE ANGLE PLATE.

1,414,970.

Specification of Letters Patent. Patented May 2, 1922.

Application filed May 10, 1919. Serial No. 296,161.

To all whom it may concern:

Be it known that I, ALEXANDER W. NELSON, a citizen of the United States, residing in the city of Newark, county of Essex, and State of New Jersey, have invented certain new and useful Improvements in Adjustable Angle Plates, of which the following is a full, exact description, such as will enable others skilled in the art to which it pertains to make, construct, and use the same, reference being had to the accompanying drawings, and to letters of reference marked thereon, forming a part of this specification.

This invention relates to adjustable angle plates, and the object of my invention is to provide an angle plate having the usual two flat and true surfaces, one at right angles to the other, pivotally mounted upon a base or support and provided with means for turning and locking the angle plate in any angular position relative to said support or base, thereby increasing the simplicity of the construction and operation of the device, by decreasing the number of parts of which the usual device is composed; by lessening or avoiding the necessity for adjustment of the various parts, and by increasing the convenience in manipulation of the device.

To this end, I have made changes in this device from similar devices; all with the object of increased efficiency.

With these ends in view, my invention consists in novelties of construction and arrangements of parts as hereinafter set forth and pointed out in the claims.

While the preferred form of my invention is illustrated in the accompanying drawings, yet it is to be understood that minor changes may be made without departing from the scope thereof.

In the drawings, in which like characters of reference indicate corresponding parts throughout:—

Figure 1 represents, a side elevation of my improved device.

Figure 2 represents, a front elevation of the same.

Figures 3 and 4 represent, respectively, side and rear elevations, with some of the parts shown in section.

Figure 5 represents, a detailed view of the support.

Figures 6 and 7 represent, respectively, a side elevation and a plan view of the base

designed to be rotatively secured to the support illustrated in Figure 5.

Figures 8 and 9 represent, respectively, side and end elevations of the guide block designed to have sliding engagement with the base illustrated in Figures 6 and 7.

Figures 10 and 11 represent, respectively, a plan view and a side elevation of the bracket which is designed to be pivotally mounted upon the guide block represented in Figures 8 and 9, and

Figure 12 represents, a side elevation of the angle plate which is designed to be rotatively mounted upon the bracket illustrated in Figures 10 and 11 of the drawings.

In the drawings 1 represents a suitable support preferably of iron, which may be of any desired or convenient shape, and provided with a pair of slotted lugs or extensions 2—2, by means of which said support can be secured to a machine.

The support 1 in its upper side is recessed and provided with a beveled or tapered annular seat 3 to receive a correspondingly beveled or tapered base 4 adapted to be rotated in said support 1, in a manner to be hereinafter described.

Integrally formed upon the top of said base 4 are guides 5—5 designed to receive the guides 6 of the standard 7, which is designed to have sliding engagement with the base 4 in a horizontal direction.

These three essential elements, namely, the support 1, the base 4 rotatively mounted upon said support and the standard 7 which is slidably secured to the base 4 constitutes the support upon which is pivotally mounted the angle plate. Adjustably and pivotally secured to the standard 7 by means of a stud 8, is a bracket 9 the rear surface of which is provided with two apertured ribs 95 10—10 which straddle the standard 7, which is correspondingly apertured to receive said stud 8, and by means of which said bracket is pivotally secured to said standard 7.

The front of the bracket 9 is similarly recessed as the support 1 and likewise provided with a beveled or tapered annular seat or surface 11 to receive a correspondingly beveled or tapered extension 14 formed on the rear surface of the angle plate 12, the work surface of the angle plate 12 contains slots or guide-ways 13 to receive the bolts used to fasten the work. It is to be under-

stood that the lower surface of the support 1 is likewise provided with a flat and true surface, so that when the parts are in the position illustrated in the drawings, a 5 movement of approximately 90 degrees or more of the angle plate 12 may be obtained.

These two essential elements, namely, the bracket 9 and the angle plate 12, which is rotatively mounted upon said bracket, constitute 10 the angle plate proper which is pivotally secured upon the support.

In order to impart rotary motion to the angle plate 12, a worm wheel 13, is preferably formed integral therewith, adjacent to 15 the tapered extension 14 which engages with the annular seat 11 of the bracket 9.

This worm wheel 13 engages with a worm 15 secured to a shaft 16 which is suitably mounted in the lower portion of the bracket 20 9, the end of said shaft 16 projecting outside of said bracket and having secured thereto a handle 17.

The beveled or tapered extension 18 of the angle plate 12 is provided with suitable 25 graduations so that the plate 12, may be accurately set to any desired degree by means of the worm 15 and worm wheel 13. The angle plate 12 is further provided with a centrally arranged stud 19, said stud being 30 screw threaded to receive a screw threaded tapered washer 20, and a lock nut 21, the tapered washer being designed to be received by the tapered aperture formed in the rear face of the bracket 9, and by means of which 35 the said angle plate 12 is secured to the bracket.

In order to impart rotary motion to the base 4, a worm wheel 22, is formed integrally with the underside of the said base, 40 said worm wheel 22, designed to engage with a worm 23 which is formed on one end of a shaft 24 suitably mounted in the support 1. The end of the shaft 24 projecting outside of said support being provided with a 45 handle 25. A stud 26 centrally secured to the underside of the base 4, is screw threaded at its free end and designed to have screw threaded engagement with a tapered washer 27 and a lock nut 24.

50 The tapered washer 27, being designed to be received by the tapered aperture formed in the underside of the support 1 and by means of which the base 4 is secured to the support.

55 The beveled or tapered upper surface of the base 4 is provided with suitable graduations 28 so that the base 4 may be accurately set to any desired degrees by means of the worm wheel 22 and worm 23.

60 The edge of one of the ribs 10 of the bracket 9, has formed integrally therewith a worm segment 29 designed to have engagement with a worm 30, mounted upon a shaft 31 suitably located in the standard 7, 65 the end of said shaft 31 being provided with

a handle 32. By means of the segmental worm wheel 29, and the worm 30, the bracket 9 carrying the face plate 12, can be adjusted to any angle desired. The outer face of the rib 10, is also provided with graduations 33. 70

The ends of the stud 8 by means of which the bracket 9 is pivotally secured to the standard 7, are screw threaded to receive screw threaded tapered washers and lock nuts. The tapered washers being designed 75 to engage with the tapered apertures formed in the faces of the ribs 10.

Suitably located on the top surface of the base 4, is an apertured lug 34 which has engagement with the screw 35, one end of 80 which has screw threaded engagement with a screw threaded hole 36 formed in the standard 7, by means of which the standard may be adjustably and slidably secured upon said base 4, as clearly illustrated in the 85 drawings.

Experience has demonstrated that the organization above described is a highly efficient one, and while I have shown the preferred embodiment of my present invention, 90 I do not wish to be limited to the exact details of construction shown and described, as obvious modifications thereof, not involving the exercise of invention, may be made by any skilled mechanic, and such departures 95 from what is herein set forth, I consider within the scope and terms of my claims.

Having thus described my invention, what I desire to secure by Letters Patent is:—

1. A device of the character described, comprising a support, provided with a recessed and beveled annular seat, a base provided with a correspondingly beveled portion rotatively mounted upon the annular 105 seat of said support, a standard slidably secured to the base, a bracket adjustably and pivotally secured to the standard provided with a recessed and beveled annular seat, an angle plate provided with a correspondingly 110 beveled portion rotatively mounted upon the said bracket and means for changing the angular position of said angle plate.

2. A device of the character described, comprising a support, a base rotatively 115 mounted upon said support, a standard slidably secured to the upper surface of the base, a bracket adjustably and pivotally secured to the standard and an angle plate rotatively mounted upon said bracket.

3. A device of the character described, comprising a support, adapted to be secured to a machine or the like, a base mounted upon said support provided with means adapted to be engaged by means carried by 125 said support for rotating said base upon said support, a standard slidably secured to the upper surface of the base, a bracket adjustably and pivotally secured to the standard, means located on said bracket designed to 130

engage with means carried by said standard for changing the angular position thereof, an angle plate rotatively mounted upon said bracket and provided with means carried by said angle plate to engage with means carried by said bracket for rotating the same.

This specification signed and witnessed this 8th day of May, 1919.

ALEXANDER W. NELSON.
